COMBINED CAN COVER AND CLOSABLE POURING SPOUT

Peter Innvar, Melville, Michael Loos, Oakdale, and John
B. Nicholson, West Islip, N.Y. (all % 26 Grand Ave.,
Farmingdale, N.Y. 11735)

Filed Dec. 27, 1968, Ser. No. 15,130

Term of patent 14 years

Int. Cl. D9—02

U.S. Cl. D9—275

FIG.1

FIG.2

FIG. 3

FIG. 1 is a perspective view of a combined can cover and closable pouring spout showing our new design with the pouring spout open;

FIG. 2 is a perspective view with the pouring spout closed; and

FIG. 3 is an enlarged cross sectional view taken on the line 3—3 of FIG. 1 with the pouring spout cover and attaching element being omitted for convenience of illustration.

We claim:

The ornamental design for a combined can cover and closable pouring spout, substantially as shown.
